ELECTRICAL RECEPTACLE PLUG

William F. McIntosh, Charlestown, Mass.

Application January 7, 1935, Serial No. 675

1 Claim. (Cl. 200—115.5)

My present invention relates to contact plugs and more particularly to an electrical receptacle contact plug.

My improved contact plug is particularly adaptable for heavy duty use where high voltage current is used such as portable drills and similar electrical devices but the principle involved in my improved plug is applicable for any use which may require a plug-in cord.

10 The principal object of my invention is therefore an improved electrical receptacle cord plug.

Another object is an electrical plug of the class described in which is combined in combination individual standard cartridge fuses.

15 Another object is an electrical fused plug in which the fuse members are maintained in positive contact by means of tension springs.

Another object is a simple means for removing and replacing burned out fuses.

20 Other objects and novel features comprising the construction and operation of my invention will appear as the description of the same progresses.

25 In the drawing illustrating the preferred embodiment of my invention Fig. 1 is a side elevation of the plug assembled.

Fig. 2 is also a side elevation as viewed at ninety degrees from Fig. 1.

Fig. 3 is a side elevation with one-half of the 30 plug casings removed and

Fig. 4 is a cross section taken on the line 4—4 of Fig. 3.

Referring more in detail to the drawing, 10 and 11 comprise two duplicate halves which form the base of the plug. 12 and 13 comprise two duplicate halves which form the insulated casing of the said plug, being securely clamped together by means of the threaded screw 14 at one end and another threaded screw 15 which also passes 40 through the base members 10 and 11.

Bosses 16 and 17, formed around the screw holes in the bases 10 and 11 on the inner sides of the said base members, are adapted to engage in recesses 18 and 19 in the broad sides of the insulated casing members 12 and 13. These recesses 18 and 19 with their engaging bosses 16 and 17 provide additional locking means between the casings 12 and 13 and the base members 10 and 11.

On the inner faces of the casings 12 and 13, I 50 have provided semi-circular grooves 20 and 21 extending from end to end of the members 12 and 13. Within the semi-circular recesses 21, I have provided a pair of duplicate contact members comprising a plug portion 22 and a base member 55 23. Base member 23 comprises a cylinder one

end of which is bored out at 24 to receive one end of a standard cartridge fuse 25 and a compression spring 26 located behind the end of the cartridge fuse as shown in Fig. 4. A recess 27 provided in the upper half of the cylindrical member 23, has its bottom connected with the outer end of the member 23 by means of an opening 28 through which electrical contact wires 29 may be inserted and pushed around the cylindrical sides of the recess 27 for the purpose of attaching 10 securely thereto by means of screws 30. The casing 12 is provided with a recess 31 in which the end of the screw 30 is inserted for the purpose of anchoring the cylindrical base member 23 in place as shown in Fig. 4.

15 Contact pins 22 are provided with a base portion 32 the rear end of which is recessed at 33 to form a receptacle 34 for the purpose of receiving the front end of said cartridge fuse. Slots 35 are provided in the member 34 for the purpose of introducing a spring tension on the end of the cartridge fuse. At 36, I have provided an annular groove which is adapted to seat over a pin 37 located in the casing 12 along the bottom of the semi-circular recesses 20 and 21, such that the contact pins 22 are securely held in place when the casing members 12 and 13 are together as shown in the drawing.

20 In actual use, the cartridges 25 may be easily removed by loosening the screws 14, 15, and 38 30 and lifting pins 22 until the annular groove 36 is raised from the pin 37 at which time pin 22 and fuse 25 may be removed and a new fuse inserted in the member 34 and re-assembled by pushing the fuse and pin 21 down against a compression spring 26 until the annular groove 36 is engaged over the pin 37, at which time the screws 14, 15, and 38 are again tightened.

25 In the two halves of the base members 10 and 11, I have provided an opening for an electrical cable 40 39 to be inserted and have provided annular ribs 40 around the inner side of the cable opening such that when the screws 38 are securely set up, the cable 39, which is the conventional heavy rubber insulated type, takes the form as shown in Fig. 45 3, the annular rib sinking into the rubber insulation of the cable 39 thereby securely locking the said cable within the base members 10 and 11.

30 While I have shown a particular modification of the use whereby my improved contact plug may be utilized, it is to be further understood that further application of the invention is intended with all types of electrical assembly.

Having thus described my invention, what I claim is:

5 An improved cartridge fuse electrical plug comprising a split insulating member and a split base member, said base member having an electrical cable opening therein and annular grooves located around the inner surface of said openings adapted to engage said cable, a cartridge fuse contact pin assembly comprising a contact pin and receptacle for one end of said fuse and a recessed base member and compression spring adapted to

receive the other end of said fuse and provide tension on the said fuse between said contact pin and recessed base members, a second recess located on said base member adjacent its back end and an offset opening connecting said recess at its bottom with the back end of said base member for the purpose of admitting electrical contact wires to said second recess.

WILLIAM F. MCINTOSH.
